ASH TRAY

Julius Tschudi, Montreal, Quebec, Canada

Application September 15, 1950, Serial No. 12,207

Term of patent 7 years

(Cl. D85—2)

To all whom it may concern:

Be it known that I, Julius Tschudi, a citizen of Switzerland, residing at 1189 Sussex St., city of Montreal, Province of Quebec, Canada, have invented a new, original, and ornamental Design for an Ash Tray, of which the following is a specification, reference being had to the accompanying drawing, forming part thereof.

In the drawing:

Figure 1 is a perspective view of an ash tray showing my new design, as seen from above; and

Figure 2 is a perspective view of said ash tray as viewed from underneath and showing the manner of removably supporting the tray to its support.

I claim:

The ornamental design for an ash tray, as shown.

JULIUS TSCHUDI.
